UNITED STATES PATENT OFFICE.

FRANCIS I. MAULE, OF PHILADELPHIA, PENNSYLVANIA.

PIPE-CUTTING IMPLEMENT.

SPECIFICATION forming part of Letters Patent No. 249,966, dated November 22, 1881.

Application filed October 3, 1881. (No model.)

To all whom it may concern:

Be it known that I, FRANCIS I. MAULE, a citizen of the United States, residing in Philadelphia, Pennsylvania, have invented certain 5 Improvements in Pipe-Cutting Implements, of which the following is a specification.

My invention relates to certain improvements in the class of pipe-cutting tools of which that described in my Patent No. 225,403, March 10, 1880, is an example, and the object of my 10 improvements, which are fully described hereinafter, is economy in the construction of the tool.

In the accompanying drawings, Figure 1 is 15 a side view, partly in section, of my improved pipe-cutting tool; Fig. 2, a section on the line 1 2, and Fig. 3 a section on the line 3 4.

The bent end *a* of the head *A* of the tool, with its angular piece *b* of hardened steel, 20 constitutes the jaw against which the pipe to be cut is forced, and by which it is prevented from turning, the head itself being preferably made of malleable cast-iron, and the portion *d* of the head being made in the form of a hollow cylinder, within which a cylindrical block, *e*, fits 25 snugly, but so as to slide freely, but is prevented from turning by the end of a set-screw, *f*, the latter extending into a longitudinal groove in the block. The cylindrical portion

30 *d* of the head is threaded internally at one end for the reception of the threaded end *h* of the nut *B*, which is screwed tight into its place, so as to become a permanent part of the head, being retained, if desired, by a suitable transverse pin or bolt. The nut is threaded internally 35 throughout a portion of its length, this portion being adapted to the threaded part *i* of the rod *D*, and the remaining portion of the interior of the nut being plain or unthreaded, 40 so as to serve as a guide for the rod and prevent the exertion of undue strain on the threaded portions of the nut and rod in manipulating the tool.

In the outer end of the block *e* is a slot for 45 receiving the rotary cutter *m*, which turns on a pin, *n*, passing through the block.

The object in making the tool in the peculiar manner described is economy in construction.

An accurate fit of the block *e* in the cylind-

rical portion of the head is insured by boring 50 the latter and turning the former, and it is well known to practical machinists that these operations—turning and boring—are the cheapest of all machine-shop processes, the cost of production being always increased by milling or 55 planing objects one of which has to fit accurately into the other, and still further increased when recourse is had to manipulative operations, such as filing or chipping.

A peculiar manner of making the handle *G* 60 of the rod *D* and securing it to the latter is another economical feature of my invention. This handle is made of cast-iron, is hollow, partly for insuring lightness, is elongated, as shown in Fig. 3, and is rounded on the edges 65 and ends. A mold is made in sand to accord with this handle, and the end portion of the rod having been introduced into the mold the molten metal is cast in the same. The rod, prior to its insertion in the mold, is flattened 70 at the end *x*, so as to form a dovetail, which is embraced by the metal on one side of the handle, the metal on the opposite side embracing the rod at *y* and serving to relieve the dovetail from undue strains. 75

The manner of using the implement in severing tubes will be readily understood without explanation.

I claim as my invention—

1. The combination of the head, its cylindrical portion *d*, and cylindrical block *e*, with the nut *B*, adapted to be screwed into the said cylindrical portion of the block, and the threaded rod *D*, adapted to the internal thread of the nut, all substantially as specified. 80

2. The combination of the rod *D*, threaded at its upper end and flared or flattened at its lower end, with the hollow handle *G*, cast around and embracing the flared end of the rod, as set forth. 85

In testimony whereof I have signed my name to this specification in the presence of two subscribing witnesses.

FRANCIS I. MAULE.
